DE WANE B. SMITH
By Milton E. Robinson

ATTORNEY

UNITED STATES PATENT OFFICE.

DE WANE B. SMITH, OF DEERFIELD, NEW YORK.

DESIGN FOR AN ATOMIZER-BODY.

SPECIFICATION forming part of Design No. 31,678, dated October 17, 1899.

Application filed October 18, 1897. Serial No. 655,630. Term of patent 7 years.

To all whom it may concern:

Be it known that I, DE WANE B. SMITH, a citizen of the United States, residing at Deerfield, in the county of Oneida and State of New York, have invented and produced a new and original Design for Atomizer-Bodies, of which the following is a specification, reference being had to the accompanying drawings and the figures marked thereon, forming a part of this specification.

Figure 1 is a perspective of the atomizer-body. Fig. 2 is another perspective from another point of view.

The material feature of the design is the shape and appearance of the atomizer-body as a whole, as shown in the drawings. The

main parts of the atomizer-body may be mentioned as follows: the cylindrical body 1, the dependent cylindrical part 2, having the spiral corrugations 2^a, and a flaring flange 3 on one end of and springing directly from the end of the body, all arranged as shown.

What I claim as new is—

The design for an atomizer-body as herein shown and described.

In witness whereof I have affixed my signature this 14th day of October, 1897, in the presence of two witnesses.

DE WANE B. SMITH.

Witnesses:

P. P. SMITH,
E. W. JONES.
